UNITED STATES PATENT OFFICE

114,711

DESIGN FOR A DRESS ENSEMBLE

Irving Grobstein, New York, N. Y.

Application March 10, 1939, Serial No. 83,488

Term of patent 3½ years

To all whom it may concern:

Be it known that I, Irving Grobstein, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is the front view of a dress ensemble showing my design;

Fig. 2 is the rear view thereof;

Fig. 3 is the front view of the dress member of the ensemble shown in Fig. 1;

Fig. 4 is a rear view of Fig. 3.

The revers and peplum of the blouse member of the ensemble have net inserts and are embroidered all over as shown.

I claim:

The ornamental design for a dress ensemble, substantially as shown and described.

IRVING GROBSTEIN.
